UNITED STATES PATENT OFFICE.

JULIUS OLESCHAK, OF PHILADELPHIA, PENNSYLVANIA.

LOCK.

SPECIFICATION forming part of Letters Patent No. 772,112, dated October 11, 1904.

Application filed March 29, 1904. Serial No. 200,504. (No model.)

To all whom it may concern:

Be it known that I, JULIUS OLESCHAK, a citizen of the United States, residing at Philadelphia, in the county of Philadelphia and State 5 of Pennsylvania, have invented certain new and useful Improvements in Locks, of which the following is a specification.

My invention relates to that class of locks in which the bolt is operated by means of a 10 rotary cylinder containing a series of transverse tumblers which are adapted to lock the cylinder by the engagement of the ends of the tumblers with slotted openings in an outer cylinder or casing.

15 The object of my invention is to improve the construction of this class of locks by making the tumblers more reliable in their operation, and by adapting in a single lock both the flat and cylindrical forms of tumblers I am 20 able to produce a lock which is extremely difficult to manipulate without the use of a properly-fitted key.

The nature of my improvements will be more 25 fully understood by reference to the accompanying drawings, forming part of this specification, in which—

Figure 1 represents a perspective view of lock embodying my improvements. Fig. 2 illustrates a vertical section taken transversely 30 through the cylinders on a line 2 2 of Figs. 1 and 4, showing the construction and arrangement of the flat tumblers. Fig. 3 shows a similar section cut transversely through the base of the lock on a line 3 3 of Fig. 4, illustrating the construction and arrangement of 35 the cylindrical tumblers. Fig. 5 illustrates a detached perspective view of two of the flat tumblers, showing the manner in which they are arranged with respect to each other when 40 placed in the tumbler-cylinder; and Fig. 6 is a detached perspective view of a washer used on either side of the bank of tumblers.

Referring to the several parts of the drawings by letters, A represents the shell or casing 45 of the lock, to which is fastened a cylinder A', provided with slotted openings a' a' to receive the ends of a series of flat tumblers.

A² is a disk-shaped enlargement formed at the base of the cylinder A', containing the 50 cylindrical tumblers and serving as a flange

for screws a a, by which the portion A is united to the cylinder A'.

B is a rotary cylinder containing a series of flat tumblers C and slotted at B' B' to receive the projecting ends of these tumblers. 55

D are slotted washers arranged within the cylinder B at the opposite ends of the bank of flat tumblers.

The tumblers C are provided with oppositely-disposed tongues C', which rest in the slotted openings B' of the cylinder B and which are caused to project beyond and into the slotted openings a' of the cylinder A' by means of spiral springs s. These springs abut at one end against the wall of the cylinder B and 60 at the other against projections c, formed upon the sides of the tumblers. As shown in Fig. 5, the adjacent tumblers C are spring-pressed in opposite directions—that is to say, the first tumbler is pressed downward by its 65 spring, while the next in order is pressed upward, and, moreover, while the spring on the first tumbler is located at the left of the tumbler the next in order is located to the right. The object of this arrangement is, first, to 70 permit the use of a key having unlike undulating sides and, secondly, to confine the springs in place by shoulders c', formed on the sides of the tumblers, which will, when 75 arranged in opposition in the series, form side walls to confine the springs in their respective places. At the front and rear of the bank of tumblers the rounded sides of the washers 80 D serve the purpose of the shoulders on the tumblers C. 85

At the base of the cylinder A', at which point is formed the enlargement A², are located openings e to receive cylindrical tumblers E, each of which is formed of two parts, one arranged above the other and acted upon 90 by springs s'. Before inserting a key into the lock these tumblers will assume the position shown in Fig. 3, and the cylinder B will be locked by the outer portions of the tumblers crossing the dividing-line between the cylinders A' and B; but with the key K in place, as shown in Fig. 4, the dividing-line of tumblers and cylinders will coincide and the cylinder B may be turned.

In the rear of the cylinder B is a plug F, 100

provided with a slotted opening *f* to receive the forward end of the key. It is also provided with an eccentric-pin *f'*, which engages a slotted opening *g* in the bolt *G* and is adapted to move the bolt when the cylinder *B* is rotated.

Having described my invention, what I claim, and desire to secure by Letters Patent, is—

- 10 1. A lock comprising a fixed cylinder and a movable cylinder, a series of tumblers arranged side by side within the movable cylinder, a spiral spring acting upon each of the tumblers to press it beyond the limits of the movable cylinder and into engagement with the fixed cylinder, and a shoulder formed upon the sides of the tumblers to retain the adjacent springs in position, substantially as specified.
- 15 2. A lock comprising a fixed cylinder and a movable cylinder, a series of tumblers in frictional contact with each other within the movable cylinder, a spring acting upon each of the tumblers to press it from the movable cylinder into the fixed cylinder and projections formed upon opposite sides of each of the tumblers one of which is adapted to engage the end of the spring and the other to retain the adjacent springs in position, substantially as specified.
- 20 3. A lock comprising a fixed cylinder and a movable cylinder, a series of tumblers arranged side by side within the movable cylinder, a spiral spring acting upon each of the tumblers to press the same into engagement with the fixed cylinder, a shoulder formed upon the sides of the tumblers to inclose and retain the adjacent springs in position and two-part cylindrical tumblers adapted to traverse openings in the fixed and movable cylinders, substantially as described.
- 25 4. A lock comprising a series of flat tumblers slotted to receive a key, a cylinder inclosing the same slotted to receive the ends of the tumblers, a spiral spring interposed between each of the tumblers and the cylinder, a slotted cylinder surrounding the first-mentioned cylinder and a two-part cylindrical tumbler, the members of which are guided in openings formed in the inner and outer cylinders so that the abutting ends of the tumbler will coincide with the dividing-line of the cylinders when a key is inserted, substantially as specified.

3. A lock comprising a fixed cylinder and a movable cylinder, a series of tumblers arranged side by side within the movable cylinder, a spiral spring acting upon each of the tumblers to press the same into engagement with the fixed cylinder, a shoulder formed upon the sides of the tumblers to inclose and retain the adjacent springs in position and two-part cylindrical tumblers adapted to traverse openings in the fixed and movable cylinders, substantially as described.

4. A lock comprising a series of flat tumblers slotted to receive a key, a cylinder inclosing the same slotted to receive the ends of the tumblers, a spiral spring interposed between each of the tumblers and the cylinder, a slotted cylinder surrounding the first-mentioned cylinder and a two-part cylindrical tumbler, the members of which are guided in openings formed in the inner and outer cylinders so that the abutting ends of the tumbler will coincide with the dividing-line of the cylinders when a key is inserted, substantially as specified.

In testimony whereof I affix my signature in presence of two witnesses.

JULIUS OLESCHAK.
